UNITED STATES PATENT OFFICE.

WILLIAM C. CODMAN, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A TEAPOT OR SIMILAR ARTICLE.

40,366.

Specification for Design.

Patented Nov. 23, 1909.

Application filed September 11, 1909. Serial No. 517,346. Term of patent 14 years.

To all whom it may concern:

Be it known that I, WILLIAM C. CODMAN, a subject of the King of Great Britain, residing at Providence, in the county of Providence and State of Rhode Island, have invented and produced a new, original, and ornamental Design for a Teapot or Similar Article, reference being had to the accompanying drawing.

The figure in the drawing is a perspective view of a tea pot, showing my design.

I claim

The ornamental design for a tea pot or similar article, as shown.

WILLIAM C. CODMAN.
